DOOR LOCK

Samuel F. Rolph and Avagim Wartian, Detroit,
Mich., assignors to The Yale & Towne Manufacturing Company, Stamford, Conn., a corporation of Connecticut

Application July 21, 1938, Serial No. 220,446

9 Claims. (Cl. 292—164)

This invention relates to a lock for an automobile door. More particularly, the invention relates to a lock of the class described in which certain operations may be obtained with a minimum number of parts, and with a minimum amount of manual manipulation.

In one form of our invention, we use a rotary bolt, and in a further modification, we use a conventional bolt of the sliding type. While the sliding type of bolt is conventional in that it slides, it is not conventional in that it is retracted to open the door through cooperation with the strike, much in the same manner as it is latched back upon the slamming of the door.

A feature of the invention is the maintenance of the sliding type of latch bolt against retraction to open the door, except when certain means are operated from either the outside or the inside of the door, and when the door is slammed shut. As an important feature of our invention, we arrange for the dogging of the outside operated means, which in this case is a push button, by the inside operated means, which in this case is a lever. Moreover, the same lever that dogs the outside push button against operation, itself releases the latch bolt for retraction when operated in a particular manner.

As a further feature of our invention, we arrange for the releasing of the dogging of the outside operated button when the door is slammed shut, should the button be dogged with the door in open position.

As still a further feature of the invention, it is possible to assemble the lock relatively to the door and the usual sliding glass window, without the employment of relatively costly mechanism heretofore required for avoiding obstructing the window operation. All of this will be clear to those skilled in the art.

More in detail, the sliding bolt modification of our invention comprises a bolt which is spring projected into locking position, this bolt cooperating with a strike whereby it latches back and forth until it reaches a locking position. The strike and bolt are so designed that a reverse pressure on the bolt by the strike is adapted to retract the latch so that the door may be opened. For preventing the retraction of the latch in this manner, we use a dogging member, which in our preferred embodiment is a slide member, and this slide may be retracted from dogging position by an inside operated lever, or by an outside operated lever. The inside operated lever, moreover, may dog the outside operated lever against operation.

When the door is slammed shut, should the outside operated lever be at the time dogged by the inside lever, the latch bolt will be retracted and will move the inside operated lever to release position. To make it possible for the bolt to

latch back, we utilize a very unique and novel mechanism for moving the dogging slide out of dogging relation to the bolt as the door is swung shut. This mechanism, in a preferred form, comprises an auxiliary bolt member which is rotatably mounted, preferably on the bolt itself, and which impinges against the strike in advance of the bolt. When so impinging, it rotates and moves the slide vertically and out of dogging relation to the bolt just in advance of the retractive movement of the bolt itself which follows immediately thereafter.

Because of the nature of our construction, we are able to use an L shaped base plate for our lock, comprising a base plate member and an end plate member. The mounting of the outside operated lever is such on the end plate that the glass may come into juxtaposition to the end plate without interfering with the operation of the lock.

In the second modification of our invention, we utilize a rotating bolt which is dogged against rotation in an unlocking direction by a slide, very similar to the slide in the first modification. Because of the nature of the bolt, the bolt itself retracts the slide in a latching manner to allow the bolt to move into locked relation to the strike. Reverse rotation of the bolt, however, is prevented by the slide member, and to allow this reverse rotation, it is necessary to retract the slide member by the inside or the outside lever, much as in the first modification.

Of course, the inside and outside levers control one another as in the first modification. We utilize the latching back or retracting of the sliding dog member by the latch bolt as it moves into locked relation to the strike to release the outside lever from the inside lever, much as in the first modification. We have thus described the two modifications of our invention generally, because we believe that this general description will be helpful in a proper appreciation of the detailed structure which follows.

In describing our invention in detail, we shall refer to the drawings wherein Fig. 1 is an elevation showing our rotary bolt lock and its relation to the operating structure. Figs. 2 and 3 are sections taken along lines 2—2 and 3—3 of Fig. 1. Fig. 2a is a section taken along lines 2a—2a of Fig. 2. Fig. 4 is a view of certain parts of Fig. 1 in a second position. Fig. 5 is a section taken along lines 5—5 of Fig. 4. Fig. 6 is a perspective view of our entire lock assembly.

Fig. 7 is a view similar to Fig. 1 of the sliding bolt lock of our invention, while Fig. 8 is a section along lines 8—8 of Fig. 7. Fig. 9 is a section along lines 9—9 of Fig. 7. Fig. 10 is a section along lines 10—10 of Fig. 7. Fig. 11 is a view of certain parts of Fig. 7 in a slightly different position.

Fig. 12 is a perspective view of essential parts of the particular structure.

For convenience, we shall first describe the sliding bolt lock of our invention. Referring now to Figs. 7-12, inclusive, and especially to Figs. 7 and 12, the frame of our lock is an L-shaped member having a base plate portion 10, and an end plate portion 11. The bolt is formed of a nose 12 riveted at 13 to a tail 14, the tail extending at 15 into a bearing member 16 carried on the base plate 10. The nose of the bolt extends through an opening 17 in the end plate 11, this opening 17 and the bearing 16 acting as guides for the bolt assembly. A coil spring 18 projects the bolt outwardly from the lock, this projection being limited by a lug 19 on the bolt tail 14 cooperating with a rubber lug 20. In Fig. 12, for convenience, the base and end plates 10 and 11 respectively are not shown, nor is the tail of the bolt, only the nose 12 and the rivets 13 being illustrated.

For locking the bolt 12 against retraction, I employ a dogging slide 21 cut away at 22 for support on a pair of studs 23 and 24 extending from the base plate 10. A spring 25 presses on the surface 26 of the slide 21, and maintains it in its position of Figs. 7 and 12 in dogging relation to the bolt 12, with its portion 21a behind the shoulder 12a of the bolt.

An inside operated lever 27 is pivoted at 28 to the base plate 10, and has a portion 29 impinging against a lug 30 struck from the slide 21. When the lever 27 rotates in a counterclockwise direction in Figs. 7 and 12, it moves the dogging slide 21 out of dogging relation to the bolt 12. A spring 31 cooperates with either one of two depressions 32 of a plate 33 forming part of the lever 27 for yieldingly holding the lever 27 in its position of Figs. 7 and 12, or in the position of Fig. 11 clockwise from its position of Figs. 7 and 12, in which position it performs a further function, to be described presently.

The end plate 11 has pivoted thereto at 35 a lever 36 which has an arm 37 adapted to be contacted and operated by a push button, to be described presently, which push button is mounted on the outside of the door, and which rotates the lever 36 about its mounting 35. The arm 38 of the lever 36 is adapted through contact at point 39 with the slide 21, to move the dogging slide out of dogging position in the same manner as it is moved by inside lever 27.

The lever 36 has a further arm 40, and it is through this arm 40 that the lever 36 is dogged against operation by the arm 41 of the lever 27. Thus, when the lever 27 is rotated in a clockwise direction from its positions of Figs. 7 and 12, the arm 41 thereof moves in behind the arm 40, as shown in Fig. 11, and blocks rotation of the lever 36 intended to move the dogging slide 21 out of dogging position.

Because of this relation of the parts, the lever 27 may rotate in one direction about pivot 28 to retract the slide 21, and may rotate in another direction to block the operation of the outside lever 36 so as to prevent release of the locking mechanism from the outside of the car, thus contributing a form of protection which is valuable in this type of lock.

Glancing now at Fig. 12, it will be appreciated that the bolt 12 is dogged against retractive movement, and were the door slammed into shut position with no means present for retracting the dogging slide 21, the door could not be shut except by operation simultaneously of one of the

levers 27 or 36. To allow the door to be slammed shut without operation of either the inside or outside levers, we utilize an auxiliary bolt 42 which is preferably pivoted at 43 on the bolt 12, and which has a tail 44 impinging against a cam piece 45 stamped out of the dogging slide 21. This auxiliary bolt 42 is adapted to contact the strike with which the bolt 12 cooperates, in advance of the bolt 12, as is probably best illustrated in Figs. 8 and 10. In Fig. 8, the strike is designated by reference numeral 46, and has two locking portions 47 and 48, so as to give a double locking action which is deemed necessary in the art.

As the door is swung shut, the auxiliary bolt 42 first impinges against the strike and moves on its pivot 43, acting through its tail 44 and cam 45 to move the slide 21 upwardly and out of deadlocking relation to the bolt 12. This movement is repeated for the second locking at 48, as will be understood, thus bringing the parts to the locking position illustrated in Fig. 8, all as is quite apparent.

We have found it desirable to provide means for releasing the outside lever 36, should that lever be locked against movement when the door is open, and the door then slammed shut. This is to prevent a locking out of the owner of the car. In order to describe this action, let us assume that the lever 27 has been rotated about its pivot 28 to bring its portion 41 in obstructing relation to the arm 40 of the lever 36, that is, to the position of Fig. 11. This, it will be noted, brings a cam piece 49 of lever 27 in rather close relation to a surface 50 on the bolt tail 14, all as is shown in Fig. 11.

Now, should the door be slammed and the auxiliary bolt 42 perform the function of moving the slide 21 out of dogging relation to the main bolt 12, the retractive movement of the main bolt will through cooperation of the surfaces 49 and 50, rotate the lever 27 back to its position of Figs. 7 and 12, or out of locking relation to the arm 40 of lever 36. This, of course, releases the lever 36 for operation from the outside, all as will be clear.

For rotating the lever 27 about its pivot 28, we may use a standard type of remote control mechanism, although any other type of mechanism is equally adaptable. For convenience, we have shown a rotating lever 51 connected through arm 52 and lever 53 to the lever 27, it being obvious that rotation of the lever 51 by a suitable handle against the pressure of a control spring 54 will serve to rotate the lever 27 either into a position to retract the dogging slide 21 from dogging position, or to rotate the lever 27 into position dogging the outside release mechanism against operation.

For rotating the lever 36 on its pivot 35 to move the dogging slide 21 out of dogging relation to bolt 12, we utilize a push button 55, or a cylinder lock 55, as the case may be. In three doors of a four door sedan, we use a push button, but in the fourth door, we use a cylinder lock. In principle, this follows the practice in the automobile industry today. As is illustrated in Fig. 8, the cylinder lock 55 is locked from the outside by the rotation of a cam 56 thereon which interlocks at 56a with a sleeve 57 forming part of the outer surface 58 of the door. This maintains the cylinder 55 against inward sliding movement necessary to operate lever 36. When the cam part 56 is out of the notch 56a of the sleeve 57, the cylinder 55 may slide inwardly in Figs. 8 and 9 and rotate the lever 36, all as is quite ap-

parent. In the case of the push button used on three of the doors, it will be possible always to apply pressure to the lever 36, but it will be impossible to rotate the lever 36 when it is locked by the arm 41 of lever 27 from the inside.

We have now described the operation of bolt 12 and its locking by the slide 21. We shall now describe how the bolt 12 is retracted from its locked position of Fig. 8 to permit the opening of the door. Granted that in Fig. 8 the dogging slide 21 is moved to release the bolt 12, it is necessary to understand how the bolt is retracted. Examination of bolt 12 will illustrate that it is beveled on both sides in such a manner that it will cooperate with the strike surfaces 47 and 48 in a manner to force the bolt 12 rearwardly against the pressure of its spring 18 when a pull is exerted on the outside handle 59, or when pressure is exerted against the door from the inside in the direction of the arrow 60 in Fig. 8. The operation from the outside will be as follows:

Should the lever 36 not be dogged from the inside by an occupant of the car, pressure on push button or lock cylinder 55 from the outside will rotate the lever 36, causing it to move dogging slide 21 out of dogging position. A pull on the handle 59 will now cam the bolt 12 back, opening the door. This novel construction has actually been applied to automobiles, and has been found extremely desirable and fully operative.

A notable advantage of our construction is illustrated best in Fig. 8, wherein it will be seen that the glass 61 extends in very close proximity to the end plate 11. This illustrates the possibility in our lock of having an extremely narrow door frame, whereby vision may be improved, all of which will of course be apparent to those who have studied the particular problem, and who know of the many costly mechanisms which have been developed to make possible a narrow window frame.

We shall now refer to Figs. 1-6, inclusive, wherein we show a form of our invention in which we utilize a rotary latch bolt 62 formed with four teeth 63, and mounted for rotation on end plate 11 on the axis of a shaft 64. The shape of the bolt 62 and its teeth 63 is probably best illustrated in Fig. 2a. Secured on the shaft 64 for rotation therewith simultaneously with bolt 62 is member 65 having teeth 66 shaped similarly, but not exactly like teeth 63 of bolt 62.

In Figs. 2a and 3, there is shown at 67 a strike having portions 68 adapted to interlock with the teeth 63 of the bolt 62. The operation of bolt 62 and the member 65 is such that the two parts 62 and 65 may rotate freely in a direction to interlock the bolt and strike, that is, to the position of Fig. 2. A reverse rotation of the bolt 62 and its part 65 is prevented by a lug 69 on a dogging slide 70, which is similar to dogging slide 21 in most particulars. Thus, the slide 70 is similarly mounted on the base plate 10, is similarly spring pressed in a locking direction, and is similarly retracted out of dogging position through a lever 71, which is almost identical with lever 27 of my first modification.

The lever 71 acts to lock a lever 36 against operation from the outside exactly the same way as in the first modification described (Figs. 4 and 5). The lever 36 in turn retracts the dogging slide 70 in the same manner as in the first modification through the use of arm 38. For throwing off the locking of the lever 36 by the lever 71, we utilize a construction which is but slightly different in detail from that of the first modification. The

dogging slide 70 and its lug 69 are adapted to be moved against the pressure of the spring 25 as the bolt 62 and its part 65 rotate in a locking direction, it being obvious that the slide will move up and down until, when the bolt is in the position of Fig. 2, the parts will assume the position of Fig. 6. As was explained previously, reverse rotation of bolt 62 is of course prevented with the parts in the position of Fig. 6.

If the door is open and the lever 71 is moved into position to lock the lever 36 against rotation to retract the dogging slide 70 (Figs. 4 and 5), should the door be slammed shut, the following action will take place: The bolt 62 and its part 65 will be rotated into locking relation to the strike, and during this rotation will move the slide 70 upwardly against its spring 25, as was already described. This upward movement will cause the upper surface 72 of the lug 69 to abut the under surface 13 of the arm 74 of lever 71, moving the lever from its locking positions of Figs. 4 and 5 into its position of Fig. 6, all as is quite apparent.

The lever 71 is controlled much in the same manner as is the lever 27 of the first modification, that is, by a remote control handle 75, illustrated in Fig. 1. Rotation of the handle 75 into the position marked deadlocked, will, through suitable means rotate the lever 71 into its dot and dash line position of Fig. 1, in which position the outside operated lever 36 will be locked against operation. If, on the other hand, the handle 75 is rotated into unlocking position, the slide 70 will be moved vertically from the position of Fig. 6, releasing the member 65 for rotation. This, of course, releases the bolt 62 for rotation to release position.

The outside operated lever 36 is controlled by a push button or cylinder lock 55, this being exactly the same construction as described in the first modification. When the push button 55 operates lever 36, a pull on the handle 59, which is exactly like the handle of the first modification, causes a rotation of the bolt 62, allowing the door to move to fully open position.

We believe that the operation of our invention will now be quite clear to those skilled in the art.

We now claim:

1. In a lock of the class described, a base plate, an end plate substantially at right angles thereto, a bolt mounted for locking movement relatively to said end plate, a locking slide for said bolt mounted on said base plate, a lever on said base plate for retracting said slide from locking position, and a second lever on said end plate and adapted also for retracting said slide, said first lever being movable also into a position in which it blocks movement of said second lever.

2. In a lock of the class described, a base plate, an end plate substantially at right angles thereto, a bolt mounted for locking movement relatively to said end plate, a locking slide for said bolt mounted on said base plate, a lever on said base plate for retracting said slide from locking position, a second lever on said end plate and adapted also for retracting said slide, said first lever being movable also into a position in which it blocks movement of said second lever, and means whereby said first lever is moved through the movement of said bolt incidental to the slamming shut of the door, whereby to release said second lever.

3. In a lock of the class described, a base plate, an end plate substantially at right angles thereto, a rotary bolt mounted for rotation on a pivot supported on said end plate, a locking slide for said

rotary bolt mounted on said base plate, a lever pivoted on said base plate for retracting said slide from locking position, and a second lever pivoted on said end plate and adapted also for retracting said slide, said first lever having means whereby when moved into a predetermined position it blocks movement of said second lever.

4. In a lock of the class described, a base plate, an end plate substantially at right angles thereto, a rotary bolt mounted for rotation on a pivot supported on said end plate, a locking slide for said rotary bolt adapted to lock said bolt against release rotation while being itself retracted by locking rotation of said bolt, a lever pivoted on said base plate for retracting said slide from locking position, and a second lever pivoted on said end plate and adapted also for retracting said slide, said first lever being movable also into a position in which it blocks movement of said second lever, said first lever being movable by retraction of said slide incidental to locking rotation of said bolt whereby to release said second lever.

5. In a lock for a door, a strike, a sliding bolt spring pressed into cooperation with said strike, said bolt and strike having cooperating surfaces whereby said bolt is retracted by contact with said strike when said door is moved in an opening direction and when said door is moved in a closing direction relatively to said strike, a deadlocking slide for said bolt, an auxiliary bolt mounted to contact said strike in advance of said bolt when said door moves in a closing direction and to be moved through said contact, means whereby said auxiliary bolt when so moved moves said deadlocking slide out of deadlocking relation to said bolt, and inside and outside operated devices also adapted to move said deadlocking slide out of deadlocking relation to said bolt.

6. In a lock for a door, a strike, a sliding spring pressed latch bolt, a dogging mechanism for preventing retraction of said latch bolt, means contacting said strike in advance of said latch bolt when the door is slammed shut adapted to release said latch bolt from said dogging means prior to contact of the latch bolt with the strike, an outside operated device for releasing said latch bolt from its dogging mechanism, an inside operated device and means whereby in one position it releases said latch bolt from said dogging mechanism while in another position it renders said outside device ineffective to release said latch bolt from its dogging mechanism, and means whereby the retraction of said latch bolt as when the door is slammed shut releases said outside device from control of said inside device.

7. In a lock of the class described comprising a base plate and an end plate extending substantially at right angles from said base plate, a rotary bolt of the type rotated by contact with a strike into locking relation to the strike, means mounting said bolt for rotation on the end plate, a spring pressed locking slide for locking said bolt against rotation in any one of several rotated positions, means mounting said slide on said base plate, said bolt pressing said slide against its spring as said bolt rotates into locking position, a lever pivoted on said end plate and operable from the outside of the lock for pressing said slide out of locking position, a second lever mounted on said base plate and operable from the inside and movable into two positions, means whereby in one position of said

lever it holds said slide out of locking position, a portion of said second lever blocking operation of said outside operated lever when said second lever is in its second position, and means on said slide cooperable with said second lever when it is in its second position for moving it out of said second position when said slide is pressed against its spring incidental to the rotation of the bolt into locking relation to its strike.

8. In a lock of the class described comprising a base plate and an end plate extending substantially at right angles from said base plate, a rotary bolt of the type rotated by contact with a strike into locking relation to the strike, means mounting said bolt for rotation on the end plate, a spring pressed locking slide for locking said bolt against rotation in any one of several rotated positions, means mounting said slide on said base plate, said bolt pressing said slide against its spring as said bolt rotates into locking position, a lever pivoted on said end plate and having a portion thereof extending substantially at right angles to said end plate and substantially parallel to the base plate, said extending portion being operable from the outside of the lock for pressing said slide out of locking position, a second lever mounted on said base plate and operable from the inside and movable into two positions, means whereby in one position of said lever it holds said slide out of locking position, a portion of said second lever blocking operation of said outside operated lever when said second lever is in its second position, and means on said slide cooperable with said second lever when it is in its second position for moving it out of said second position when said slide is pressed against its spring incidental to the rotation of the bolt into locking relation to its strike.

9. In a lock of the class described comprising a base plate and an end plate extending substantially at right angles from said base plate, a rotary bolt of the type rotated by contact with a strike into locking relation to the strike, means mounting said bolt for rotation on the end plate, a spring pressed locking slide for locking said bolt against rotation in any one of several rotated positions, means mounting said slide on said base plate, said bolt pressing said slide against its spring as said bolt rotates into locking position, a lever pivoted on said end plate and having a portion thereof extending substantially at right angles to said end plate and substantially parallel to the base plate, a push button on the outside of the lock for pressing against said extending portion and thereby moving said lever to press said slide out of locking position, a second lever mounted on said base plate and operable from the inside and movable into two positions, means whereby in one position of said lever it holds said slide out of locking position, a portion of said second lever blocking operation of said outside operated lever when said second lever is in its second position, and means on said slide cooperable with said second lever when it is in its second position for moving it out of said second position when said slide is pressed against its spring incidental to the rotation of the bolt into locking relation to its strike.
